SELF-FREEING ICE TRAY

Donald Branch Knight, Brooklyn, N. Y., assignor,
by mesne assignments, to General Motors Corporation, a corporation of Delaware

Application April 16, 1931, Serial No. 530,501

21 Claims. (Cl. 62—108.5)

This invention relates to trays adapted to be inserted in evaporators or cooling elements of household mechanical refrigerators for containing foods and desserts to be congealed or water and other liquids to be frozen.

A considerable problem is presented in the removal of trays after the freezing operation has been accomplished on account of their sticking to the shelves or other supporting surfaces.

It is an object of the invention to provide in conjunction with an ice tray a device for automatically freeing the tray from the bottom and sides of the ice freezing compartment in which the tray is placed to freeze its contents.

Further objects and advantages will be apparent from the following description taken in connection with the accompanying drawings, wherein:

Fig. 1 is a fragmentary, front elevation illustrating one application of the invention;

Fig. 2, a fragmentary, longitudinal section taken on the line 2—2 of Fig. 1;

Fig. 3, a similar view with the parts in the position they assume after freezing;

Fig. 4, a fragmentary, longitudinal section of a modified form;

Fig. 5, a similar view with the parts in the position they assume after freezing;

Fig. 6, a fragmentary, longitudinal section of another modified form;

Fig. 7, a fragmentary, longitudinal section of a further modified form;

Fig. 8, a fragmentary bottom plan view taken on the line 8—8 of Fig. 7;

Fig. 9, a fragmentary, longitudinal section of a still further modified form; and

Fig. 10, a fragmentary bottom plan view of the tray of Fig. 9.

Referring to the drawings, an evaporator 10 or freezing element of any desired construction is provided with a number of compartments 11 formed by the sides of the evaporator, and shelves 12. The compartments 11 are of a size to accommodate ice trays 13 capable of holding water or other substances, such ice trays being formed of any desired material and having handgrips 14 by means of which they may be removed. Water or other liquid spilled over the sides of the tray when inserting in the evaporator will freeze, as well as moisture condensed upon the exterior of the trays, and cause the trays to stick tight so that considerable difficulty is encountered in removing them. In order to cause the trays to free themselves after their contents become frozen, a bellows 15 filled with water is placed under the

front end of the tray or handgrips 14. On account of the fact that the front end of the tray is the last to freeze the water in the bellows is the last to congeal and the resulting expansion will lift the front end of the tray from the shelf 12 as shown in Fig. 3, after which the tray may be readily removed.

In lieu of the construction just described the construction shown in Figs. 4 and 5 may be employed. With this construction an ice tray 16 of slightly modified form is provided with a recess 17 for the accommodation of an expandible vessel 18 adapted to contain water or other liquid which will expand upon freezing and lift the ice tray free, breaking the ice which is frozen around it so that the tray may be easily removed. The invention not only contemplates expandible members such as those illustrated, but other desirable applications of the invention will be apparent. For example, in Fig. 6 there is shown an ice tray 19 provided with a depression in its under side formed by the bulged up or elevated portion 20, and with a diaphragm 21 forming a chamber 22 adapted to contain water or other freezable substance. At its center the disk 21 is provided with a shelf engaging fulcrum or boss 23 adapted, when the liquid in the compartment 22 freezes, to raise the front edge of the tray from the shelf.

In Fig. 7 is illustrated a further modified construction which comprises a tray 24 having its front extremity turned downwardly and rearwardly and forming upper and lower horizontal ledges between which is disposed a bellows 25. The expansion of the bellows 25 will lift the front end of the tray as in the previously discussed embodiments of the invention. To the downwardly turned front end of the tray is attached by means of bolts or other fastening means, a handle 26. In Figs. 9 and 10 is shown a modification similar to that of Figs. 4 and 5, except that the tray 27 is not only provided with an elevated portion 28 in its front, but the front is also bent over and has attached thereto a handle 29, a rearwardly extending ledge 30 joining the handle with the under surface of the elevated portion 28. In this construction the bellows is carried by the individual tray front instead of by the tray proper. The expandible diaphragm comprises upper and lower cup members 31 and 32, the lower cup member 32 having a shelf-contacting knob 33 which rests upon the shelf 12. The bellows 15, 18 and 25 are provided with removable plugs 34, 35 and 36 by means of which the bellows may be filled.

It will be obvious to those skilled in the art

- that various other changes may be made in the construction and arrangement without departing from the spirit of the invention and therefore the invention is not limited to what is shown
- 5 in the drawings and described in the specification, but only as indicated in the appended claims.
- I claim:
1. In combination with an ice tray, an expansible member containing a substance which expands upon freezing for breaking the tray entirely free from a supporting shelf after the major portion of the substance in the tray has been frozen.
  - 10 2. In combination, an ice tray, a support for said tray, and a freezing-water thermostat adapted to move said tray relative to its support.
  - 15 3. In combination with a tray having a handle, a support for said tray, and a freezing-water thermostat constructed to exert a force between the handle and the support for lifting the tray from the support.
  - 20 4. In apparatus of the class described, a tray, and a device adapted to exert force against said tray for automatically moving said tray from its support comprising an expansible element containing a substance which expands upon freezing.
  - 25 5. In combination with a tray for receiving substance to be chilled, a member adapted to expand upon freezing connected to the exterior of the tray in a manner to lift a portion of the tray from a support upon freezing of the expansible member.
  - 30 6. In combination with a tray for receiving matter to be chilled, a liquid-containing expansible member connected to the exterior of the tray in a manner to lift a portion of the tray from a support upon freezing of the liquid within the expansible member.
  - 35 7. In combination, a tray having an indented portion, a support for the tray, and an expansible member within said indented portion for exerting pressure between the tray and its support.
  - 40 8. In combination, a tray having an indented portion, a support for the tray, and an expansible member within said indented portion for exerting pressure between the tray and its support operable upon freezing.
  - 45 9. In combination, a tray having an indented portion, a support for said tray, and a freezing thermostatic member within said indented portion for moving the tray relative to its support.
  - 50 10. In combination, a tray having an indented portion, a front plate for said tray, a support for said tray, and a freezing thermostatic member within said indented portion and attached to said front plate for exerting pressure between the tray and its support.
  - 55 11. In combination, a tray having a depression in the bottom, a support for the tray, a flexible member covering said depression and forming a fluid-tight chamber, a portion of said flexible member engaging said support, and matter within said chamber which expands upon freezing, whereby the tray will be lifted from its support upon the freezing of the expansible matter.
  - 60 12. In combination with an ice tray having a

recess on its under side, a bellows in said recess, and a substance within said bellows adapted to expand the bellows upon being changed from a fluid to a solid.

13. An evaporator for a refrigerator including a support, a tray adapted to contain matter to be changed by transfer of heat relative thereto when resting on said support, and an expansible member constructed to urge said support and tray apart upon the transfer of heat. 10
14. A cooling device comprising, in combination, a cooling element, a shelf supported by the element, a slideable container supported by the shelf, and a temperature responsive motor for breaking an ice bond between the container and the shelf. 15
15. A cooling device comprising, in combination, a cooling element, a shelf supported by the element, a slideable container supported by the shelf, and a temperature responsive bellows containing a freezing solution operatively connected to said container for moving at least a portion of the container away from the shelf at a predetermined temperature range. 20
16. A cooling device comprising, in combination, a cooling element having a support member formed thereon, a receptacle member adapted to contain a substance to be congealed or frozen associated with the support member of the cooling element, and means primarily influenced by the temperature of the substance to be congealed or frozen for controlling the position of one of said members relative to the other of said members. 25
17. A cooling device comprising, in combination, a cooling element having a support formed thereon, a receptacle adapted to contain a substance to be congealed or frozen associated with the support of the cooling element, and temperature responsive means including an element carried by said receptacle and movable relative thereto for moving at least a portion of said receptacle relative to said support. 30
18. An ice tray having a contact surface for engagement with a cooling element and means outside the contact surface to automatically exert force between the tray and said element angularly to said surface to release an ice bond between the surface and the element. 35
19. An ice tray having a contact surface for engagement with a cooling element and means outside the contact surface and responsive to decrease of temperature to automatically exert force between the tray and said element angularly to said surface to release an ice bond between the surface and the element. 40
20. An ice tray having a contact surface for engagement with a cooling element and a device which changes its volume when affected by heat to automatically exert force between the tray and said element angularly to said surface to release an ice bond between the surface and the element. 45
21. An ice tray having a contact surface for engagement with a cooling element and a member outside the contact surface and actuated by expansion of a freezing substance other than substance contained in the tray to automatically exert force between the tray and said element angularly to said surface to release an ice bond between the surface and the element. 50
